AIR HUMIDIFICATION APPARATUS

Vincent S. Day, Summit, N. J., assignor, by
mesne assignments, to Carrier Engineering
Corporation, Newark, N. J., a corporation of
New York

Application June 1, 1931, Serial No. 541,242

7 Claims. (Cl. 126—113)

This invention relates to a unit apparatus for conditioning an atmosphere, and more particularly to an arrangement for humidifying a volume of air treated by the unit.

5 The general object of the invention is to provide a water circulating system, including an evaporator and affording means for controlling the temperature of the water, and hence the rate of evaporation in conditioning systems, where desired volumes of air are treated at one point and then distributed by means of a fan or otherwise to the conditioned area, and where it is desirable to control both the temperature and relative humidity of the air at the point of conditioning. 10 The requirements of temperature and humidity, however, may vary or may change, and not at the same rate. Thus, a high or low temperature may be desired for different purposes with different relative humidities. The problem of controlling the humidity, therefore, independently of the temperature, and yet arrange for both temperature and humidity control in a single compact unit, is a difficult one, since the factors affecting the one condition must be kept independent of those relating to the other. 15

A feature of the invention resides in the arrangement of an evaporator in combination with a circulating system served by a source of heat independent of an associated heating apparatus 20 forming part of a unified system. The positioning of the evaporator in a location substantially removed from the influence of heating apparatus belonging to the same air conditioning unit allows the rate of evaporation to be controlled independently of the heating process carried on for temperature control.

Another feature resides in the positioning of the evaporator at the point of discharge of the air served by the unit, so that effective humidification may take place and the evaporation process aided.

Another feature covers the employment of a heating drum as part of the circulation system having an outlet readily accessible from without the unit. This enables the circulation system to be speedily drained and the drum easily cleaned and scaled. Since the drum is subjected to relatively high temperatures, its interior should be periodically cleaned in order that circulation may not be impeded. The feature providing for easy access is not merely for convenience alone, but insures maintaining the evaporation process at maximum efficiency.

A further feature provides for a water circulation system used for humidification purposes

in an air conditioning unit wherein one part is located within a fire box of the unit and the rest of the system is located outside. Means are provided for effectively separating the fire box area from the rest of the unit at the points of connection of the portions of the circulating system within and without the fire box.

Other objects and features, covering advantages of design and construction, and making for economy in operation, will be more apparent from the following detailed description of one form of the invention, to be read in connection with the accompanying drawings, in which:

Fig. 1 is a diagrammatic representation of an air conditioning apparatus incorporating a humidification system in accordance with the invention.

Fig. 2 is a detail showing an arrangement for feeding water to the humidification system.

Figs. 3 and 4 illustrate the accessibility of the heating drum and the method of applying heat to the water circulation system.

Fig. 5 is a plan view of the piping and circulation arrangement, and

Fig. 6 is a detail showing the method of segregating the water drum of the circulation system from the rest of the unit.

Considering the drawings, similar designations referring to similar parts, numeral 7 designates, generally, an air conditioning unit suitable for controlling the temperature and relative humidity of an enclosure connected by ducts to outlet 8. The apparatus includes inlet 9 for air from any desired source, filters 10, fan 11, fire box 12, burners 13 within the fire box for heating air, burners 14 for heating water drum 16, shield 15 segregating water drum 16 from the rest of the fire box, interchangers 17 and 18, header 19, cooling chamber 20 for products of combustion, diverter 21 for mixing products of combustion with air drawn in from surrounding atmosphere and flue 22. As indicated by the arrows, the air is drawn through inlet 9 is first filtered and then sent to the conditioning portion of the unit by the fan. Part of the air proceeds above the fire box and through the first interchanger, whereas another portion goes directly to the second interchanger. Still another part of the air is routed around the fire box and bypasses the interchangers. This bypassed air, however, is forced in close proximity to trough 23 of the humidification arrangement.

The humidification apparatus comprises a water circulating system, including open water trough 23, water channels or pipes 24 and 25

heating drum 16, and a float arrangement 30 (hereinafter described in detail) adapted to maintain a predetermined level of water within the trough 23. The float arrangement 30 (Fig. 2) 5 is mounted near the trough 23 and a pipe connecting the two has its discharge adjacent the entrance of pipe 25. Cool water from 30 enters the trough and establishes a temperature differential between the water at one end of the 10 trough and at the other. Hence, a circulation of water between the drum 16 and the trough 23 will be established by thermosyphon action. The drum is located within the fire box, but is effectively segregated from the effect of the burners 13 by the confining shield 15. The drum is therefore subject only to the influence of its 15 related set of burners 14 which serve the humidification system and remains uninfluenced by the burning equipment used for temperature control 20 of the air served by the unit. In order to confine the products of combustion within the fire box, elements 26 provide sealing joints at the points where pipes 24 and 25 enter the fire box. These pipes are connected to the drum in any suitable 25 manner. In the arrangement shown in Figs. 5 and 6, elements 26 are mounted in contact with wall 27 of the fire box and are retained in sealing position by spring 28 arranged between the element and fitting 29. The water in the humidification 30 apparatus is retained at a desired level by means of float apparatus 30, of any usual type, connected to a source of supply. For example, the float arrangement 30 comprises a tank in communication with trough 23. Within the tank 35 is a float adapted to operate a valve, thereby controlling the admission of water to the tank from any suitable source, in response to changes in the level of water therein. Since the tank and trough 23 are in communication, it is obvious 40 that the float, in responding to changes in level in the tank, simultaneously responds to changes in the level of water in the trough. Figs. 3 and 4 show the assembly of the drum in the unit, with its independent burners 14, served by gas 45 supply from any desired source through pipe 31, and more particularly denote the ease with which the interior of drum 16 may be made accessible. As illustrated, drum 16 terminates in a flange 32 suitably mounted in the outer wall 33 of the 50 unit. Any method of fixing the drum in position may be utilized, the important feature being to have the flange or extremity of the drum at the outer wall of the unit apparatus. In the particular arrangement illustrated, flange 32 receives cover 34 which is securely bolted to the 55 flange, suitable packing or gasket being employed in the usual manner. The cover may, therefore, be quickly removed from outside the unit, making the interior of the drum available for cleaning 60 of scaling. If desired, a spigot or drain 35 may be fitted within the cover so that the humidification system may be drained before the cover is removed. Since it may often be inconvenient to remove the cover on one side of the unit, similar 65 assembly is provided on opposite sides, so that the drum is accessible from either side and easily cleaned.

In practice, some of the air entering the unit will be sent around partitions or shielding 36 70 which effectively separates the heating apparatus from the trough 23. This air will, therefore, remain substantially unaffected by the heating apparatus and will be subject only to the influence of evaporation taking place from the open faced trough. The rate of evaporation will depend 75

upon the operation of burners 14 serving the drum, and these burners may be controlled in any suitable manner to provide desired humidification. It may be noted that the air passing between partition 36 and the outer extremities of the unit will pass in close proximity to the trough and be deflected by baffle 37 downwardly toward the trough. The resultant intimacy of contact between the moving air and water, which, in practice, is at times so great as to agitate the water, affords great efficiency in securing maximum humidification. After leaving the trough, the humidified air enters outlet 8 and thence to the area served by the unit. It may be noted that air collecting tube 38 which is used for removing heated air for raising the temperature within flue 22 is so positioned that it will not remove any humidified air, all of which is free to proceed to the area served in accordance with specified requirements. 10 15 20 25 30 35 40 45 50 55 60 65 70 75

It is of note that the provision of drum 16 within the fire box makes for efficiency in assembly and marked economy in operation. The burning equipment for humidification and heating is thus concentrated at one point of the apparatus, and yet independent heating is provided for the humidifier, separate and unrelated to the air heater. Also, the provision of burner equipment at the bottom of the unit, where it most logically belongs, enables maximum circulation between the drum and the evaporator comprising 25 through 23 which is best adapted to function at the top of the unit, apart from and uninfluenced by the heating equipment, and in position where maximum contact with the air will take place 30 prior to direct discharge from the unit. The provision of the trough near outlet 8 assures issuing the humidified air at the temperature it leaves the unit, since it then has no opportunity to be affected by any of the heating apparatus in the 40 unit. Humidification, therefore, remains independent at all points in the unit, without relation to the apparatus for heating the air. 45 50 55 60 65 70 75

Since certain changes may be made in the above construction and different embodiments of the 45 invention could be made without departing from the scope thereof, it is intended that all matter contained in the above description or shown in the accompanying drawings shall be interpreted as illustrative and not in a limiting sense. 50 55 60 65 70 75

Having described my invention, what I claim as new and desire to secure by Letters Patents, is:

1. In an air conditioning unit, a casing, a firebox in said casing, a heat interchanger in communication with said firebox, a fan for supplying air to said casing, the surfaces of said firebox and said interchanger forming a passageway for the main portion of air supplied by said fan, air humidifying means, and a partition between said firebox and said casing, said partition forming a passageway with said casing for diverting a portion of the air supplied by said fan to said humidifying means, said partition forming a passageway with said firebox for diverting another portion of the air supplied by said fan over the surfaces of said firebox to cool it. 55 60 65 70 75

2. A combination of apparatus for heating and humidifying air, a casing, a firebox in said casing, a heat interchanger in communication with said firebox, an evaporator comprising an open water trough, a fan for supplying air to said casing and over the outer surfaces of said interchanger, a conduit for supplying a portion of air from said fan over said evaporator without contacting said 70 75

interchanger, a first set of burners in said firebox, an enclosed water drum in said firebox, a shield between said first set of burners and said water drum, a plurality of pipes connecting the drum and the evaporator, and a second set of burners for heating said water drum to cause a circulation of water through said drum, said pipes and said evaporator.

3. A combination of apparatus for heating and humidifying air, a casing, a fan for supplying air to said casing, a firebox in said casing, a heat interchanger in communication with said firebox, a passageway formed by the outer surfaces of said interchanger and a portion of said firebox for the main portion of air supplied by said fan, an evaporator comprising an open water trough, a partition between said casing and a portion of said firebox, a first passageway formed between said casing and said partition for conveying a small portion of the air supplied by said fan over said evaporator without contacting said interchanger, a second passageway formed between said partition and said firebox for conveying another small portion of the air supplied by said fan over the surfaces of said firebox to cool said firebox and substantially to prevent the heating of air in said first passageway, a first set of burners in said firebox for heating said interchanger, a water drum in said firebox, a plurality of pipes between said water drum and said evaporator, and a second set of burners in said firebox for heating said water drum to cause a circulation of water through said drum and said evaporator.

4. A combination of apparatus for heating and humidifying air, a casing, a fan for supplying air to said casing, a firebox in said casing, a heat interchanger in communication with said firebox, a passageway formed by the outer surfaces of said interchanger and a portion of said firebox for the main portion of air supplied by said fan, an open water trough, a conduit for conveying a small portion of the air supplied by said fan over said water trough without contacting said interchanger, a first set of burners in said firebox for heating said interchanger, an enclosed water drum in said firebox, a plurality of pipes connecting said drum to said water trough, and a second set of burners in said firebox for heating said water drum to cause a circulation of water through said pipes and said trough.

5. A combination of apparatus for heating and humidifying air, a heat interchanger in said casing, a fan for supplying air to said casing and for discharging the main portion thereof over said interchanger, an evaporator comprising an open water trough, a conduit for conveying a small

portion of the air supplied by said fan over said evaporator without contacting said interchanger, a first set of burners for heating said interchanger, an enclosed water drum, a pair of pipes for connecting said drum to said evaporator, a second set of burners for heating said drum to cause a circulation of water through said pipes and said evaporator, and a firebox for containing said water drum and both of said sets of burners.

6. A combination of apparatus for heating and humidifying air, a casing, a fan for supplying air to said casing, a firebox in said casing, a heat interchanger in communication with said firebox, means in said firebox for heating said interchanger, a passageway formed by the outer surfaces of said interchanger and a portion of the outer surfaces of said firebox for the main portion of air supplied by said fan, a partition between said casing and a portion of said firebox, an open water trough mounted between said casing and said partition, an enclosed water drum in said firebox, a plurality of pipes between said drum and said water trough, means in said firebox for heating said drum to cause a circulation of water through said pipes and said water trough, a first passageway between said partition and said casing for conveying a portion of the air supplied by said fan over said water trough without contacting said interchanger, a second passageway between said partition and said firebox for conveying another small portion of air over said firebox without contacting said water trough or said interchanger, and a duct for collecting air from all of said passageways.

7. A combination of apparatus for heating and humidifying air, a casing, a fan for supplying air to said casing, a firebox in said casing, a heat interchanger in communication with said firebox, a passageway formed by the outer surfaces of said interchanger and a portion of the outer surfaces of said firebox through which the main portion of air supplied by said fan is passed, an open water trough, a passageway for conveying a small portion of the air supplied by the fan over said water trough without contacting said interchanger, a conduit for collecting air from both of said passageways, a first set of burners in said firebox for heating said interchanger, an enclosed water drum in said firebox, a plurality of pipes connecting said drum to said water trough, and a second set of burners in said firebox for heating said drum to cause a circulation of water through said pipes and said water trough.

VINCENT S. DAY. 55
